Shipman & Tatum Co.

UNITED STATES PATENT OFFICE.

ROBERT B. TATUM, OF HELENA, ARKANSAS.

IMPROVEMENT IN HORSE-POWERS.

Specification forming part of Letters Patent No. 123,745, dated February 13, 1872.

To all whom it may concern:

Be it known that ROBERT B. TATUM, of Helena, in the county of Phillips and State of Arkansas, has invented a new and valuable Improvement in Horse-Powers; and doeshereby declare that the following is a full, clear, and exact description of the construction and operation of the same, reference being had to the annexed drawing making a part of this specification and to the letters and figures of reference marked thereon.

Figure 1 of the drawing is a representation of a side view of my invention. Fig. 2 is a plan view thereof. Fig. 3 is a vertical section.

This invention has relation to horse-powers; and the novelty consists in the general construction and disposition of parts composing and connected with the main driving-wheel, whereby the latter is rendered stronger and more secure, as hereinafter described.

In the drawing A represents a vertical shaft, journaled to the sill B and frame C. D designates radial arms or spokes mortised to the upper part of the shaft A, and supporting at their outer ends, which are notched, a wheel, E, of large diameter. This wheel is designed to be a gear-wheel, so as to convey motion and power by engaging with another wheel connected with the machinery to be driven. F represents long radial arms, mortised to the shaft A some distance below the wheel E. These arms are used as draft-poles, and are furnished with hooks or other equivalent devices, G, to which horses may be hitched. H designates braces secured to the shaft A; thence extending upward and outward in diagonal and radial directions to the arms or

spokes D, to which they serve as supports. The ends of the braces H are slotted so as to fit the spokes D. I denotes staples, secured to the wheel E, and arranged so as to embrace every alternate spoke. The poles F run parallel to the spokes unprovided with the staples I. J denotes posts standing at a slight inward incline upon the arms or poles F. The upper ends of said posts are slotted and receive the ends of the arms D running parallel to the poles F. In such position the posts J serve as braces to strengthen the poles F and arms D in their positions. A direct connection is made between each of the poles F and the wheel E by means of an iron rod, K. To each of the poles F a lateral security is given by means of iron rods f, coupled to staples g g' inserted in the sides of said poles, and in the sides of the arms D last mentioned. Each of the rods f reaches diagonally from one of said arms to the next pole on the right or left, as the case may be.

What I claim as my invention, and desire to secure by Letters Patent, is—

In a horse-power, the arrangement of the center-post A, wheel E, horizontal spokes D, draft-poles F, oblique struts H, diagonal braces f, and vertical struts J, all constructed substantially as and for the purposes specified.

In testimony that I claim the above I have hereunto subscribed my name in the presence of two witnesses.

ROBERT B. TATUM.
